FREDERICK W. WAKEFIELD, GERALD L. BASIL, AND CARL A. SCHROEDER, OF VERMILION, OHIO, ASSIGNORS TO THE F. W. WAKEFIELD BRASS COMPANY, OF VERMILION, OHIO, A CORPORATION OF OHIO.

LIGHTING FIXTURE.

Application filed December 6, 1923. Serial No. 679,014

The present invention relates to a bracket type of lighting fixture and more particularly to a fixture adapted for ready attachment to walls, furniture and the like and

5 provided with socket attaching means so as to be readily installed. This type of fixture is particularly adapted for installations where permanent wall fixtures can not be employed and is supplied with means for 10 several types of attachment so that it can be employed in fitting up rooms where permanent fixtures are already in place but where it is desirable to have wall brackets for the time being or for particular occasions.

15 The annexed drawings and the following description set forth in detail certain mechanism embodying the invention, such disclosed means constituting, however, but one 20 of various mechanical forms in which the principle of the invention may be used.

In said annexed drawings:—

Fig. 1 is a perspective view of the fixture; Fig. 2 is a vertical sectional view of the 25 same; Fig. 3 is a sectional view showing the fixture as applied to a bed post or the like; Fig. 4 is a sectional view on the line 4—4 of Fig. 2; and Fig. 5 is a fragmentary perspective view showing a detail of construction.

The present fixture comprises an attaching plate 1 having an outwardly extending curved socket holding arm 2 carrying the usual bulb socket 3. The plate 1 and arm 35 2 are integrally formed from a single sheet of metal, the arm being rolled to form a cylindrical tube open at the bottom while the socket holding end is in the form of an inverted cup 4 having a central aperture 5.

40 The socket is secured in place by a bushing 6 having an extension 7 passing through the aperture 5 and held in place in the lamp socket by means of a set screw 8. Thus the bracket is formed from a single sheet 45 of metal and the necessary stiffness is obtained by rolling the arm into tube like shape. The socket is provided with the usual extension cord 10 and base plug 11 for attachment to a wall outlet or other socket 50 and the cord 10 is fitted within the open tubular arm, being held in place by ears 12 formed integrally with the arm and bent

over the cord after it is inverted in the tube. There are two such ears shown but the number may of course be increased for certain 55 conditions.

The present fixture may be used as a supplementary wall bracket or side light and for such use the plate is provided with screw holes 15 through which attaching screws 60 may be inserted. Where it is desired to attach the device to the back of a piece of furniture, a U-shaped spring clip 16 is provided which is attached to the back of the plate by a screw 17 passing through one 65 of the screw holes 15, a screw headed bolt 18 being inserted in the other hole and extending through a slot 20 and being provided with a wing nut 19 for clamping the clip tightly to the piece of furniture as best 70 shown in Fig. 2.

It may also be desirable to attach the device to a post such as a bed post or the like and for this purpose, the plate is provided with one or more pairs of slots 21 75 adapted to receive straps 22 which may be fastened around the post 23 as illustrated in Fig. 3. The wires or extension cord may be connected to any suitable source of current supply but preferably the plug 11 will be 80 connected to a base board outlet or any convenient lamp socket.

The entire device is a single piece with the exception of the standard lamp socket which is attached thereto, thus facilitating 85 manufacture and eliminating joints and the like. The device is a supplementary fixture adapted for universal attachment and provided with the necessary extension cord and plug so that it may be easily attached and 90 connected wherever desired. The various attaching features are easily mounted or removed so that the bracket can be adapted to the many uses without difficulty.

Other modes of applying the principle 95 of our invention may be employed instead of the one explained, change being made as regards the mechanism herein disclosed, provided the means stated by the following claim or the equivalent of such stated means 100 be employed.

We therefore particularly point out and distinctly claim as our invention:—

A lighting fixture comprising a single

sheet of material formed with an attaching plate at one end and having an outwardly extending arm bent to form a tubular arm open at the bottom and provided with ears
5 adapted to be bent to hold the wires in said tube, said arm having its outer end formed into an inverted cup provided with a central

aperture to act as a lamp socket holding member.

Signed by us, this 4th day of December, 1923.

FREDERICK W. WAKEFIELD.

GERALD L. BASIL.

CARL A. SCHROEDER.
